UNITED STATES PATENT OFFICE.

MATTHEW GOULD, OF BELFAST, IRELAND, ASSIGNOR TO CHARLES McCLOSKEY AND HENRY McCLOSKEY, OF BELFAST, IRELAND, TRADING AS CHARLES McCLOSKEY & COMPANY.

HEMSTITCH-MACHINE.

No. 892,372.

Specification of Letters Patent.

Patented June 30, 1908.

Application filed October 5, 1906. Serial No. 337,558.

To all whom it may concern:

Be it known that I, MATTHEW GOULD, a subject of the King of Great Britain, residing at 64 Christopher street, Belfast, Ireland, 5 have invented certain new and useful Improvements in Hemstitch-Machines, of which the following is a specification.

This invention relates to sewing machines of the class in which the needles are caused to 10 vibrate or move laterally.

The object of my invention is to so make such machines that two (or more) parallel and adjacent rows of special ornamental stitching can be made on fabrics.

15 The special stitching produced by means of my invention I term "double hemstitch."

Under my invention there are two needles arranged side by side, or one may be a short distance behind the other, and secured in 20 needle blocks on the lower end of the needle bar, said blocks being vibrated by means of connecting arms and rods jointed to a vibrating quadrant or quadrants said quadrant or quadrants being operated by means of a 25 special cam. The special cam and the feed mechanism are so arranged as to give a special movement to the needles and the cloth, the combined movements producing the "double hemstitch" stitch.

30 In order that my said invention may be clearly understood I have hereunto appended an explanatory sheet of drawings, whereon,

Figure 1 is a side elevation of an ordinary Wheeler & Wilson spoke stitch or hemstitch 35 sewing machine with my invention applied thereto. Fig. 2 is a diagram showing the stitching. Fig. 3 is a view of the special cam. Fig. 4 is a view of a sewing machine with a double "quadrant" movement. Fig. 5 is a 40 plan of part of Fig. 4. Fig. 6 is a detail of the feed mechanism. Fig. 7 is a face view of the stitch or feed cam. Fig. 8 is a view of the feed raising and drop cam. Fig. 9 is an enlarged detail in elevation showing the arrangement of the punches. Fig. 10 shows in 45 diagram the disposition of the needles and punches. Fig. 11 is a detail of the feed mechanism.

Referring to the drawings:—The machine 50 *a* has vibrating needles *b*, *c*, secured in needle blocks *d*, *e*, fitted pivotally in such manner on a cross bar *f* at the lower end of the needle bar *g* that one of the needles is slightly behind the other.

55 The needles are vibrated by ordinary con-

nnections such as arms *h*, *h*¹, and connecting rods *i*, *i*¹, adjustably fitted to the ordinary "quadrant" *j* which latter is vibrated about its pivot *k* by means of a special form of cam *o* which is shown enlarged at Fig. 3. 60

When the needles are in line with each other they are in what I may call their "in" position and when they are moved laterally away from each other to their greatest extent they are in what I may term their "out" position. 65

The special cam *o* and the feed mechanism are arranged to give the following movements:—Both needles descend and enter the cloth *l* simultaneously in their "in" position 70 at 1, 1, and then open or move apart in the cloth and, when they rise again, the cloth is given a backward movement and at the next descent of the needles they are in their "out" position and enter the cloth at 2, 2. When 75 they rise again the cloth is moved forward and the needles thereafter descend in their "out" position and enter the cloth at 3, 3. At the next descent of the needles the cloth is given a backward movement and the needles 80 in their "in" position enter the cloth at 4, 4, thus completing the movement. The corresponding positions are marked on the cam *o*, 1, 2, 3, 4. The motions are repeated as often as desired to produce the required stitching. 85

When there are two "quadrants" such as shown at *m*, *n*, Fig. 4 then the connecting rods *i*, *i*¹ may be arranged as shown. The quadrant *m* is fulcrumed at *m*¹ and the quadrant *n* at *n*¹, and the fulcrum pins are extended through bearings as shown at Fig. 5 and connected together by arms *p*, *p*¹, which latter are jointed together at *p*² so that when the quadrant *m* (which is alone operated by the cam) is moved in one direction the quadrant *n* is moved in the opposite direction. The special cam for operating the quadrants is the same as before. In this case the movements of the needles are the same and the stitch is also the same as before. 95

When the needles are arranged side by side and close together then the arrangement is such that they enter the cloth simultaneously and when they rise again the cloth is given a backward movement, the needles 105 then open out and again enter the cloth. When the needles rise again the cloth is moved forward and then the needles, still apart, again enter the cloth. When the needles again rise the cloth is given a further 110

backward movement and when the needles again descend they enter the cloth close together. When the needles rise again the cloth is moved forward and so on. These 5 movements are repeated as often as desired to produce the stitching.

The above movements of the needles are effected by means of the special cam which has suitable projections for the purpose. It 10 will be seen from Fig. 3 that the cam *o* has a groove *o*¹ in which the pin of the quadrant *j* or *m* works. When the needles enter the cloth the first time the pin is at 1, when they enter the cloth the second time the pin is at 15 2, when they enter the cloth the third time it is at 3 and when they enter the cloth the fourth time the pin is at 4 and so on, the movements being repeated. The dotted lines, Fig. 2, indicate the movements of the 20 needles.

The cam *q* is a cam such as used in other machines of this class and is illustrated in face view at Fig. 8. This cam causes the feed bar to rise and fall at the proper times 25 by means of the connections *x*⁰, *x*⁵, and rocking shaft *x*⁶, see Fig. 11. The cam *t* transmits a translational movement to the feed bar *v* through the quadrant *x*, rod *y*¹ and rocking shaft *x*³, see Figs. 6 and 11. 30 When the needles *b*, *c*, enter the cloth at 1 (Fig. 2) the pin in quadrant *j* is in position 1 in the cam groove *o*¹ (Fig. 3). On the needles and punches ascending and leaving the cloth, the latter is fed backward due to the action of 35 the roller in groove *t*¹ passing over the operative part 1 of the cam *t*. The needles and punches now descend and enter the cloth at 2, the pin in the quadrant *j* being at the position 2 in the cam groove *o*¹. On the needles 40 and punches leaving the cloth, the latter is fed forward due to the action of the part 2 of the cam *t* on the operating roller therein and through the connections with the same to the feed bar. The needles and punches again 45 descend and enter the cloth at 3, the pin in the quadrant *j* being in position 3 in the cam groove *o*¹. On the needles and punches rising and leaving the cloth the latter is fed backward owing to the action of the feed bar 50 through its connections to the cam *t*, the operating roller in the latter being now in position 3 (Fig. 7). The needles now descend and enter the cloth at point 4, the pin on the quadrant *j* being at position 4. On the 55 needles and punches rising and leaving the cloth the latter is fed forward due to the action of the part 4 of the cam *t* through the connections *x*, *x*², *y*¹ and the rocking shaft *x*³ on the feed bar. The same action is now re- 60 peated over and over again.

In openwork stitching, punches are employed and these punches are, or may be, arranged in conjunction with the needles so as to make the openings in the cloth at the proper 65 positions. There may be one, two, or three

punches as desired and these punches may be fitted to the needle bar or to a special punch bar.

Of course the mechanism employed to produce the stitch may be altered or varied according to the type of machine used and the fabric on which the stitching is to be made. 70

Having now fully described my invention what I claim and desire to secure by Letters Patent is:—

1. A sewing machine having two needles arranged on the needle bar, one behind the other and in the line of feed, means for operating the needle bar, means for moving the needles laterally, means for feeding the cloth 80 and means for causing the needles to first enter the cloth in line with one another then to move the cloth backward and the needles laterally so that they enter the cloth for the second time out of line with one another, then 85 for moving the cloth forward and again causing the needles to enter the cloth when out of line with one another then for moving the cloth backward and causing the needles to enter the cloth in line with one another. 90

2. A sewing machine having two needles arranged one behind the other on the needle bar, and in line of feed, means for operating the needle bar, means for causing the needles during the formation of the stitch to first 95 enter the cloth in line with one another, then out of line with one another, again out of line with one another and finally in line with one another again and means for causing the cloth to move alternately backward and forward during these movements of the needles. 100

3. In a sewing machine, two needles mounted one behind the other in the line of feed on a needle bar, means for reciprocating the needle bar, means for shifting the needles laterally, feeding mechanism for moving the fabric back and forth under the needles, the various elements being so timed in operation that the needles enter the goods in proximity to each other, are moved laterally in a 110 direction transversely to the feed and away from each other during a backward movement of the feeding mechanism, are reciprocated twice in line with and during a forward movement of the feeding mechanism and are 115 finally moved laterally to their first position into proximity during a backward movement of the feeding mechanism.

4. In a sewing machine, two needles arranged one behind the other in the line of feed 120 on a needle bar, means for operating the needle bar, a cam for moving the needles laterally, feeding mechanism for moving the fabric back and forth under the needles, the various elements being so timed in operation 125 that the needles enter the goods in proximity to each other, are moved laterally in a direction transversely to the feed and away from each other during a backward movement of the feeding mechanism, are reciprocated 130

twice in line with and during a forward movement of the feeding mechanism and are finally moved laterally to their first position into proximity during a backward movement of the feeding mechanism.

5. In a sewing machine, two needles mounted one behind the other in the line of feed on a needle bar, means for reciprocating the needle bar, means for shifting the needles laterally, feeding mechanism for moving the fabric back and forth under the needles, the various elements being so timed in operation that the needles first enter the cloth in line with one another, then move laterally apart 10 from one another while in the cloth, then rise and enter the cloth again when laterally apart from one another, then rise again and thereafter again enter the cloth while laterally apart from one another, and then to 15 move inwards and again enter the cloth in line with one another.

6. In a sewing machine, two needles mounted one behind the other in the line of feed on a needle bar, means for reciprocating

the needle bar, means for shifting the needles laterally, feeding mechanism for moving the fabric back and forth under the needles, the various elements being so timed in operation that the needles first enter the cloth in line with one another, then move laterally apart 25 in the cloth, and, when they rise again, the cloth is given a backward movement, and thereafter the needles are caused to again enter the cloth while laterally apart from one another and when they rise again the cloth is 30 moved forward and the needles caused to again enter it when laterally apart from one another, then the cloth is moved backward and the needles caused to again enter the cloth in line with one another, substantially 35 as described.

In testimony whereof I affix my signature in presence of two witnesses.

MATTHEW GOULD.
